United States Patent Office.

ALBERT E. ROSS, OF HOLLIS, MAINE.

Letters Patent No. 78,019, dated May 19, 1868.

IMPROVEMENT IN SAWING-MACHINES.

The Schedule referred to in these Letters Patent and making part of the same:

TO ALL WHOM IT MAY CONCERN:

Be it known that I, ALBERT E. ROSS, of Hollis, in the county of York, and State of Maine, have invented a new and useful Improved Sawing-Machine; and I hereby declare the following to be a full, clear, and exact description thereof, which will enable others to make and use my invention, reference being had to the accompanying drawings, forming part of this invention, in which—

Figure 1 shows a side elevation of my invention.

Figure 2, an end elevation, showing the gears and the manner of operating the saw.

Figure 3, a side view of the method of regulating the saw.

The object of my invention is to produce a machine for sawing wood and lumber, driven as hereinafter described, and so constructed that the saw will be thrown out of the wood automatically when the piece is cut by the saw. It also consists in a method of confining or keeping still the wood or lumber while being sawed.

My machine is set upon a frame composed of certain upright and horizontal pieces, shown at A. This frame is so constructed as to afford a convenient means of attaching the different operating parts of the machine thereto. The frame or support also carries the table, a, upon which the lumber is placed and held. b is a crank on the shaft e, which extends horizontally through the machine, and at the other extremity has a bevelled gear, d. f is a transverse shaft, with a smaller gear, e, matching d, by which revolution is transmitted from one shaft to the other. f has a balance-wheel, g, and a driving-wheel, h. To this driving-wheel h is attached, on a pivot, the arm i, also jointed or pivoted to the slide j in the guides k k. These guides are set in uprights 1, 2, &c. l is another arm, also pivoted to the slide j, and jointed like the other, and connecting with the saw-frame m.

By the operation of these jointed arms and slides a direct backward and forward motion is given to the saw-frame m by the rotation of the driving-wheel h. The frame m is arranged in a slot in the upright, n, as seen in fig. 1.

The saw and frame are made so as to lift up or fly up when the sawing of any particular piece of lumber is concluded, in order that it may be out of the way, and ready for application to pieces of timber of different thickness.

This operation is effected as follows, and by the following devices: o is a slide in the upright n. The slide works in a groove, and is connected at its lower end to a fixed spring, p, which always tends to draw the slide downward. The upper end of the slide o has two cords, q r, passing up over rolls, s t. q has a hand-piece or knob, u. r passes down on the opposite side of the upright, n, and is attached to the slide v, which slide moves in the same slot with the saw-frame, and has a truck to allow the easy backward and forward motion of the saw, even when the slide rests on the frame. The slide o has also a pin, x, which, when the slide is drawn upward, passes over the shoulder y on the pivoted lever z. The upper end of z bears against the pawl or lever a'. The spring p presses against the lever z, thus keeping this lever pressed against a', and enabling the pin x to rest on the shoulder y, but the weight of the saw-frame, when it brings the pin b' against a, will counteract the force of the spring p, and thus allow the saw to be thrown upwardly. From the slide v depends a weight to keep the saw pressed down on the wood.

The operation of these devices is as follows: Draw downward upon the knob u when the machine is to be started. This draws upward the slide o, and its pin x, passing over the shoulder y, secures and holds in place the levers z a', and by allowing the cord r to pass up over its truck in the top of the upright, n, permits the saw to work down to a point a little lower than the table a, thus insuring the complete cutting off of the wood. When the saw has worked down to the point a little below the table a, and the wood is cut, the pin b' strikes lever a', which turns on its pivot and throws the shoulder y of the lever z out from under the pin x. The slide o is thus released, and, being drawn quickly down by its spring p, it draws on the cord r attached to the slide v, raising it, and with it the saw-frame m. The weight of the saw-frame m is intended to be sufficient to release the slide o, as hereinbefore described.

e' is a hinged lever, pivoted to one of the horizontal bars of the frame A at the top. d' is another similar

lever, connected with c' by the cross-piece e' , pivoted to both c' and d' . d' has the spring h' , which tends to push upwardly.

c projects over the table a , and has teeth k' to enter the wood or lumber m' . d' is fitted with a metal edge to catch the teeth of a vertical toothed rack on one of the upright posts of the frame A. By pressing downward on d' the wood is secured while being sawed, and the levers are held by the teeth of the vertical toothed rack.

Upon releasing the metal edge of d' from the teeth, the spring h' will throw up the levers, and allow the wood to be moved along on the table a .

It is to be observed that the machine can be operated by one person, standing so as to reach the crank, b , being thus able to manipulate the wood, manage the levers c' d' , turn the crank, b , and control the saw m .

What I claim as my invention, and desire to secure by Letters Patent, is—

The combination of the slide o , lever z , lever a' , cords q r , spring 8 , and slide v , as and for the purposes set forth.

ALBERT E. ROSS.
